UNITED STATES PATENT OFFICE.

THORSTEN VON ZWEIGBERGK, OF PRESTON, ENGLAND.

CONTROLLER.

No. 839,250.

Specification of Letters Patent.

Patented Dec. 25, 1906.

Application filed May 21, 1906. Serial No. 317,869.

To all whom it may concern:

Be it known that I, THORSTEN VON ZWEIGBERGK, a citizen of the United States, residing at Preston, in the county of Lancaster, England, have invented a certain new and useful Improvement in Controllers, of which the following is a full, clear, and exact description, reference being had to the accompanying drawings.

10 The object of this invention is to provide a governing and reversing controller in a very simple and compact form.

My invention may be embodied in a crane-controller wherein the controlling-barrel is 15 horizontally located on top of the box containing the resistance. In such controller it is important to have the barrel short to prevent excessive width of the structure. In accomplishing this I place the governing-20 segments on one side of the barrel and the reversing-segments on the opposite side of the same barrel, appropriate contact-fingers being provided. I provide a double set of contact-fingers for the governing-segments and 25 a single blow-out device for the two sets. The arrangement of the contact-fingers and blow-out to allow access to the interior and the arrangement of the operating-lever also contribute to the efficiency of my controller.

30 The various features of the invention, of which the more important are above mentioned, are hereinafter more fully described, and definitely summarized in the claims.

The drawings clearly disclose my invention.

Figure 1 is a sectional front elevation of the controller. Fig. 2 is a sectional side view at right angles to Fig. 1. Fig. 3 is a partial central section parallel with Fig. 2. Fig. 4 is a partial front view sectioned through the operating-lever substantially on the line 4-4 of Fig. 3. Fig. 5 is a detail in cross-section on the line 5-5 of Fig. 3. Fig. 6 is a perspective view of the controller mounted on a resistance-box, the cover of the controller being removed. Fig. 7 is a diagram illustrating the circuits.

As shown in Fig. 6, there is preferably a box A, which forms the support for the controller and may contain the resistance. The controller-frame, composed of a horizontal member B and the vertical frame-plates C and C', rest on the box and are secured thereto. The frame member B extends down into

the box, as shown in Figs. 1 and 2, and has a 55 cross-web b, on which are mounted the reversing-fingers, as hereinafter explained. Secured to the frame member B are a pair of cross-bars D, each of which carries a block of wood E, on which are mounted brackets F, 60 which carry the contact-fingers G G'.

The controller-barrel is formed by a cylinder of wood H, mounted at its ends in metallic caps J, which have trunnions j j', extending into bearings in the plates C C'. On the 65 trunnion j is secured a lever K, by which the barrel may be oscillated to operate the controller. Mounted on the upper part of the barrel are the contact-segments N, which are adapted to coöperate with the contact-fingers G and G', some of the segments coöperating with contact-fingers of both sets. The 70 particular arrangement of the contact-segments will be hereinafter explained.

On the under portion of the barrel H are 75 secured the segments of the reversing-switch, of which two, p' and p'', appear in Fig. 1. The particular arrangement of these segments is shown in the diagram. For the present it is sufficient to say that they are curved plates 80 secured to the barrel and cross-connected, as desired, and that coöperating with the segments are the contact-fingers Q, carried by brackets S, which are mounted on the wooden block O, carried by the plate b, above referred to.

It will be seen from the above description that a very compact controller is produced. By locating the governing-segments on one 90c half of the controller-barrel and placing the reversing-segments on the opposite half the barrel need be only substantially half as long as with the reversing-segments beyond the governing-segments.

The support for the contact-fingers by 95 brackets mounted on cross-blocks of wood secured to frame members, as shown, is very simple and efficient. These finger-brackets F may be secured to the wooden blocks by screws, as shown. The brackets have upwardly-extending ears f, in which are pivoted the fingers G and G'. These fingers consist of a contact portion g, carried by the spring g', and a pivoted supporting portion g'', to which the spring is secured. A set-screw g'' 100 screwing through the contact portion and bearing against the supporting portion, forms 105 a proper adjustment. The supporting por-

tion g^2 extends rearward from its pivot in the form of a tail g^4 , which is adapted to project through a notch in a latch-lever I, which is pivoted between the ears f. When this latch-lever is in the position shown in Figs. 1 and 6, it engages the tail g^4 and holds the finger in such position that the contact portion may bear upon the segments. A spring member g^6 , carried by the finger in this position, bears on the bracket F, insuring a good electric contact. The tail g^4 extends downward slightly near its end, so as to catch behind the web of the latch-lever I, thus preventing accidental displacement. If, however, the body of the finger is pressed downward slightly, the latch-lever may be turned away to free the tail and the entire finger swung upwardly on its pivot to allow access to the barrel of the controller. These brackets F have tubular binding-posts f' , as shown, which are adapted to receive the leads M and M', coming up from the interior of the box A.

I provide a single blow-out device for the two sets of contact-fingers G and G'. This blow-out device, broadly speaking, is formed after the manner of the blow-out described and claimed in my Patent No. 691,693, issued January 21, 1902. It comprises, as shown, a metallic core t, around which is an insulating-sleeve t' , and surrounding the sleeve are insulating-plates t^2 , adapted to extend downward between the various sets of contact-fingers and segments. In the pockets formed between these plates are coils of wire t^3 , the successive coils winding in opposite directions. Surrounding the coils are the metallic tubular shields t^4 . The terminals of the windings are connected with plates t^5 on the ends of the blow-out, which plates have fingers t^6 , adapted to extend between a pair of contact-springs t^7 , carried by one of the wooden blocks E and connected with a pair of contact-fingers of the reversing-switch.

The operation of the blow-out, as explained in my patent referred to, is to stretch the spark around the metallic shield t^8 , and thus blow it out. As the segments engaging the fingers G and G' may draw away from the fingers in either direction, I extend the field of the lines of force to the opposite sides of the contact-fingers by inserting metallic plates t^9 into the separating-shields t^2 . The lines of force thus pass directly across the spark whichever way the segments move from the contact-fingers.

The structure of the blow-out is braced by bolts t^{11} , passing through the shields and through distant sleeves t^{12} , between them. Nuts t^{13} on the bolts hold the structure together and by occupying pockets c on the inner side of the frame members C C' (see more particularly Fig. 6) form a support for the blow-out. At the same time they allow the blow-out to be lifted entirely out of the frame

when the controller-cover is removed, or the blow-out may be swung upward, the nuts on one end forming a pivot. When the blow-out is thus out of the way, the contact-fingers G G' may be swung upward on their pivots, as heretofore explained.

The operating-lever K, by which the barrel is oscillated, has at its upper end a spade-handle k, adapted to be conveniently grasped by the operator. On either side of this handle are thumb-levers U U', pivoted in the yoke-frame k' of the handle. The thumb-lever U' extends below its pivot and there has a fork engaging the end of a bell-crank U², the other arm of which occupies a notch in a bolt V, slideable in the handle-frame k'. This bolt is adapted to engage notches c' c², formed on the upper edge of the frame-plate C, and thus lock the controller in any desired position. A spring Y, surrounding a rod Y', connected with the finger U' above its pivot, tends to push that lever outward, and thus press the bolt downward. The other end of the rod Y' is connected with the thumb-lever U below its pivot. This allows either thumb-lever, by being pressed toward the handle k, to withdraw the bolt, the same spring operating to press outward the two levers and press the bolt downward. This is a very simple construction and an efficient one, as it allows the handle to be grasped from either direction or by either hand with equal facility.

The notch for the off position of the controller (indicated by c²) has radial sides to prevent the displacement of the lever in either direction. The active notches c' preferably have that wall which is toward the notch c² inclined, so that the lever may be drawn from any active position to the off position at once without withdrawing the bolt V, thus allowing the current to be shut off very quickly, if desired.

The peculiar positioning of the contact-segments will be best understood from the diagram and the description of the operation. In this diagram the governing-segments are indicated by the reference characters n' to n¹⁰, respectively, and the reversing-segments by p' to p⁸, respectively. The governing-segments are in two sets, which are duplicates of each other, one set being designated with odd exponents and the other with even exponents. The controller, as shown, has six active notches in each direction, one set being for "ahead" and the other set for "reverse." In the following description we will consider the left-hand half of the diagram as for the ahead position and the right-hand half as for the reverse. Reference-numerals designate the circuits, as well as the specific contact-fingers of the sets G, G', and Q.

As shown, the two sets of contact-fingers

G and G' are a distance apart substantially equal to the distance between the "off" position and the first active position, and this distance is twice that between any of the 5 consecutive positions Nos. 1 to 6. It thus results that if the fingers G, for example, occupy (relatively to the segments) ahead position No. 1 the fingers G' will be relatively in the positions the fingers G normally occupy, while for any of the positions Nos. 2 to 6 of the fingers G the corresponding fingers of the G' set will be two positions behind.

Assuming that the controller is in ahead position No. 1, the current flows as follows, 5 it being remembered that the movement from off to the first position brings the plates which were in engagement with one set of fingers G into engagement with the other set G', so that such fingers are connected together by such plates: From the main line 1 the current flows through the armature and line 2 to the contact-finger 8, resting on the plate p⁸, to the line 3, which is connected with this contact-finger through the blow-out coil, 20 to the line 4, to the plate p⁴, to the line 5, through the field of the motor to the line 6, to the plate p'. From here it flows via the line 7 to the contact-finger 14, which is now in engagement with the segment n⁵. From 25 this segment it flows to the contact-finger 13, to the line 20, to the finger 9. With this finger connects line 21, which leads to the resistance. The current continues through the sections of the resistance R⁵, R², and R' 30 to the line 22, to the contact-finger 17, to the segment n⁹. The contact-finger 18 also engages this segment, and the current continues from this finger via the line 23, through the sections R³ R⁴ of the resistance, to the return 35 main line 24.

In the second position the contact-fingers 13 and 14 are still in engagement with the plate n⁵ and the contact-fingers 17 and 18 with the segment n⁹. Contact-finger 15 has 40 come into engagement with the plate n⁷. The circuit now flows through the motor and blow-out coil, as before, to the plate p', to the contact-finger 9, to the line 21, through the sections R⁵ and R² of the resistance, to the line 25, to the contact-finger 15, to the segment n⁷, to the segment n⁹, to the contact-finger 18, to the line 23, and through the resistance R³ and R⁴ to the return-line. The 50 movement to the second position has therefore cut out the resistance-section R'.

In the third position the finger 13 has cleared the segment n⁵ and the finger 11 has engaged the segment n'. The circuit now 55 flows from the plate p' to the finger 9, to the line 21, through the resistance-section R⁵, to the line 26, to the finger 11, to the segment n', to the segment n⁹, and, as before, to the contact-finger 18 and through the resistance-sections R³ and R⁴ to the return.

In the fourth position the contact-finger 65 16 has come into engagement with the segment n⁷, and this takes the circuit, after passing through resistance R⁵ and the line 26, to the line 27, through the resistance R⁴, and to the return.

The fifth position brings the contact-finger 70 12 into engagement with the segment n', and thus the circuit continues from the resistance R⁵ and line 26 via the line 28 to the return, cutting out the resistance R⁴.

In the sixth position the contact-finger 75 13 comes into engagement with the segment n³, wherefore the circuit from the plate p' extends via the line 20 to the segment n³, to the segment n', to the finger 12, to the line 28, to the return 24. As the controller passes from the fifth to the sixth positions the blow-out is short-circuited by reason of the finger 8 coming into engagement with the plate p⁴.

In the reverse positions the governing-circuits are identical and the reverse circuits are the same except that the circuits flow 80 through the field in the opposite direction, as will be understood from the diagram, the alternate plates p³ p⁶ and p⁵ p⁷ being respectively connected together.

I claim—

1. The combination with two sets of contact-fingers, of a double set of contact-segments, the segments on one side being in 90 the same circumferential plane with the corresponding segments of the other side, whereby said segments may each coöperate with the corresponding fingers independently to close circuits or form a bridge from the fingers of one set to those of the other.

2. A controller having a barrel and two sets of contact-segments thereon, the corresponding segments being in the same circumferential plane, and contact-fingers of which 100 two are in such plane, whereby the movement of the barrel may cause an alteration in the circuit by engaging with one of the fingers or by a segment of each set engaging with two fingers.

3. In a controller, the combination with 110 two sets of contact-fingers, of two sets of contact-segments coöperating therewith and adapted to cut in or out the resistance in the same manner for each set, and a reversing-switch moving concurrently with said segments and adapted to reverse the motor.

4. In a controller, the combination of a 120 duplicate set of governing-segments, a double set of contact-fingers, resistance connecting with the contact-fingers of each set, said controller having positions where fingers of both sets engage with the same segment, or engage either segment singly, and thereby cause an alteration in the circuit.

5. In a controller, the combination with 125 two sets of contact-fingers, of a controller-barrel carrying a duplicate set of segments,

- and means for positioning said barrel to cause segments on each side to engage the respective fingers and to cause in another position segments of one set to engage fingers of the other set and to cause in another position segments of one set to engage fingers of both sets, all such engagements changing the circuits. 65
6. In a controller, a rotatable barrel, reversing-segments on one side thereof, and two sets of governing-segments on the other side thereof, said sets being duplicates combined with suitable coöperating contact-fingers whereby the government may be the same for either direction. 70
7. In a controller, the combination of a barrel, reversing-segments secured on one side thereof, segments secured on the opposite side thereof, a set of reversing-fingers and two sets of governing-fingers. 75
8. In a controller, the combination of a horizontal barrel, reversing-segments secured on the under portion thereof, governing-segments secured on the upper surface thereof, reversing-fingers below the barrel and governing-fingers above the barrel. 80
9. In a controller, the combination of a frame having a depending portion with a horizontal member, reversing-fingers insulatingly carried by said member, a pair of vertical plates carried by said frame, a horizontal barrel journaled in said plates, reversing-segments secured to said barrel on its under side and adapted to coöperate with the reversing-fingers, a duplicate set of governing-segments secured to the upper side of the barrel, and fingers to coöperate with said governing-segments. 85
10. In a controller, the combination with two sets of contact-fingers, of a controlling member having two sets of contact-segments, and a single blow-out device for both sets. 90
11. The combination, of a controller-barrel, two sets of segments carried thereby, two sets of fingers, some of the segments being adapted to engage fingers of either set, and a blow-out device adapted to blow out the spark whichever way the segment leaves the finger. 95
12. In a controller, the combination of a horizontal barrel, reversing-segments secured on the under portion thereof, governing-segments secured on the upper portion thereof, a set of reversing-fingers carried below the barrel, two sets of governing-fingers above the barrel, and a blow-out device above the barrel adapted to act for both sets of sparks. 100
13. The combination of a horizontal controller-barrel, segments on the upper side thereof, pivoted contact-fingers above the segments adapted to bear thereon, and a movable blow-out device above the fingers and segments. 105
14. The combination of a horizontal controller-barrel, segments thereon, contact-fingers adapted to coöperate therewith, a pivoted blow-out above the contact-fingers, said blow-out comprising coils connected with a pair of exposed terminals mounted on the blow-out structure, and spring-terminals with which said exposed terminals connect when the blow-out is in position, whereby the blow-out may be easily removed. 110
15. In a controller, the combination of a pivoted contact-finger having a projection, and a latch-lever adapted to engage such projection to hold the finger in place or be turned aside to release the finger. 115
16. In a controller, the combination of a bracket, a contact-finger pivoted thereto and having a projecting tail, a latch-lever pivoted to said bracket and having a shoulder which said tail may engage. 120
17. In a controller, the combination of a bracket having a pair of ears, a contact-finger pivoted to said ears and having a hooked portion projecting rearwardly from the pivot, a latch-lever pivoted between said ears and having an opening through which such hooked portion may project. 125
18. In a controller, the combination of a barrel, a lever for operating it, a pair of thumb-levers carried thereby, a latching-bolt, and a connection between the same and each thumb-lever. 130
19. In a controller, the combination of a barrel, a lever for operating it and having a spade-handle, a pair of thumb-levers located at opposite ends of said handle, a bolt carried by the handle, and a connection between the same and each thumb-lever. 135
20. The combination of a controller-barrel, a lever for operating it, a bolt carried by the lever for locking it, a pair of thumb-levers, one of which is connected with said bolt, and a rod connecting a point on one thumb-lever below its pivot and a point on the other lever above its pivot. 140
21. The combination of a controller-barrel, a lever for operating it, a bolt carried by the lever for locking it, a bell-crank for operating the bolt, a thumb-lever for operating the bell-crank, a second thumb-lever, a rod connecting a point on one thumb-lever below its pivot and a point on the other lever above its pivot, and a spring acting on said rod. 145
22. In a controller, the combination of a barrel, a lever for operating the same, a bolt carried by said lever and adapted to engage in notches to lock the lever, a pair of thumb-levers pivoted on said lever and a connection between the thumb-levers and bolt whereby either thumb-lever may withdraw the bolt. 150
23. In a controller, the combination of a body, two sets of governing contact members carried thereby on one side, and reversing contact members carried thereby on the opposite side. 155

24. The combination with two sets of contact-fingers, of segments connected together and adapted to engage fingers of one set singly or fingers of both sets simultaneously whereby said segments may connect fingers of their own set or fingers of both sets to cause changes in the circuit.

25. In a controller, the combination with two sets of contact-fingers, of a double set of segments adapted to engage the contact-fingers independently or bridge the connection from one to the other, and a blow-out common to both sets.

26. The combination of two sets of contact-fingers, a contact member adapted to electrically connect fingers of the two sets, and resistance having a part connected with one set of contact-fingers and another part with the other set.

27. The combination with two sets of contact-fingers, and a contact-segment adapted to bridge fingers of the two sets, of a divided resistance whose parts are respectively connected with the two sets of fingers.

28. In a controller, the combination with two sets of contact-fingers, of a controlling member having two sets of contact-segments, and independent resistances for the two sets of fingers.

29. In a controller, the combination with two sets of contact-fingers, of a double set of segments adapted to engage the contact-fingers independently or bridge the connection

from one to the other, and a divided resistance connected one part with one set of fingers, and the other part with the other set.

30. The combination with two sets of contact-fingers, of a controller-barrel having a double set of contact-segments, the segments being positioned to be brought by the rotation of the barrel into coöperation with the corresponding fingers independently to close circuits or form a bridge from the fingers of one set to those of the other, and individual resistance - sections connected respectively with the two sets of contact-fingers.

31. The combination with two sets of contact-fingers, of a controller-barrel having a double set of contact-segments, the segments being positioned to be brought by the rotation of the barrel into coöperation with the corresponding fingers independently to close circuits or form a bridge from the fingers of one set to those of the other.

32. The combination with two sets of contact-fingers, of a double set of contact-segments positioned to coöperate with the corresponding fingers independently to close a circuit or to form a bridge from the fingers of one set to those of the other.

In testimony whereof I hereunto affix my signature in the presence of two witnesses.

THORSTEN VON ZWEIGBERGK.
